HYDROCARBON DEHYDRATION BY
DISTILLATION

George H. Shipley, Jr., and William B. Franklin,
Baytown, Tex., assignors to Standard Oil De-
velopment Company, a corporation of Dela-
ware

Application August 26, 1943, Serial No. 500,092

3 Claims. (Cl. 196—5)

The present invention is directed to a method for removing water from hydrocarbon mixtures of higher boiling point than propane by distillation. The method of the present invention is applicable to hydrocarbon mixtures heavier than propane in general but is particularly useful in the treatment of toluene containing mixtures obtained from petroleum by hydroforming operations.

It is known that water dissolved in hydrocarbons behaves with an abnormally high volatility, similar to a light hydrocarbon such as ethane or propane. In accordance with the present invention, advantage is taken of the abnormally high volatility of the water dissolved in hydrocarbons by flash vaporizing part of the total feed of a hydrocarbon fraction heavier than propane and containing dissolved water, condensing the vapors and settling the condensate to separate a water phase and an oil phase. The oil phase is added to the remainder of the feed and the mixture distilled to separate the remainder of the water from the hydrocarbons as an overhead fraction and to withdraw a substantially dry higher boiling hydrocarbon fraction.

The process of the present invention will now be described in conjunction with the drawing in which the sole figure is in the form of a diagrammatic flow sheet.

A hydrocarbon feed boiling at a higher temperature than propane and containing dissolved water enters the system through line 11. By way of example and not of limitation, a feed, which has been satisfactorily processed in accordance with the present invention, had an analysis of 1% water, 83% toluene, 15% paraffins higher boiling than toluene and 1% paraffins lower boiling than toluene. This fraction was obtained by the treatment of a suitably selected petroleum fraction in a hydroforming operation with the subsequent solvent extraction of the hydroformed material and the sulfuric acid treatment and hydrolyzation of the solvent extract with hot caustic soda solution.

The hydrocarbon fraction in line 11 passes through heater 12 and into flash drum 13. As the heated mixture enters vessel 13 its pressure is reduced allowing a portion of the dissolved water and some of the lower boiling hydrocarbons to vaporize and pass in the vaporous condition through line 14 and condenser 15 where they are again liquefied and thence into condensate accumulator 16. Vessel 16 is arranged to allow the separation of the oil and water layer into frac-

tions by settling and is preferably provided with an inner partition 17 to act as a weir. The heavier water fraction is withdrawn from vessel 16 through line 18 and the lighter oil fraction flows over the edge of weir 17 and accumulates in the end of the vessel adjacent outlet line 19.

The unvaporized liquid in flash drum 13 is removed from the bottom of the flash drum by line 20 and the oil fraction from separating vessel 16 is added thereto by means of line 19 containing pump 21. The combined material is then discharged into distillation tower 22.

In tower 22 the remainder of the water in conjunction with low boiling hydrocarbons is removed in vaporous form as overhead through line 23, liquefied by condenser 24 and discharged into separating vessel 25. Vessel 25 is constructed similarly to vessel 16 with an inner partition or weir 26 which allows the withdrawal of a hydrocarbon fraction through discharge line 27, and a water fraction through discharge line 28. A portion of the light hydrocarbons from vessel 25 is returned to tower 22 as reflux and the remainder is removed by means of outlet 29. The hydrocarbon removed from vessel 25 may contain toluene which is recoverable if desired by injecting this stream into additional recovery facilities. It is understood, that the volume of this stream is small in comparison with the amount of toluene recovered by way of line 30. A substantially water-free hydrocarbon is removed from tower 22 as a side stream by means of outlet 30. Heavy hydrocarbon material is removed from the bottom of the tower by means of outlet 31.

35 The following is given as a specific example illustrating operating conditions which have been found satisfactory in the operation of the apparatus shown in the figure. The material fed to the apparatus through line 11 was obtained by hydroforming a suitable petroleum fraction with subsequent extraction and hydrolyzation thereof to produce a charging stock having as its composition 83% toluene, 15% paraffins higher boiling than toluene, 1% paraffins lower boiling than toluene and 1% of water dissolved in the hydrocarbon mixture. This feed entered the system through line 11 at a temperature of 310° F. and was heated to 345° F. The line pressure in 11 was 140 pounds per square inch gauge and the pressure was reduced to 33 pounds per square inch gauge at the flash drum. The evaporation taking place at the flash drum reduced the temperature of the liquid therein to 315° F. The temperature of the condensed vapor discharged

into vessel 16 was 105° F. and the pressure within this vessel was atmospheric. Distillation column 22 was operated at a pressure of 10 pounds per square inch gauge. Of the feed charged into the system through line 11, 0.5% was removed as water through line 18 from the preliminary flashing step and 0.5% was removed as water through line 28 as a separated overhead fraction. 15% of the charge was removed as bottoms through line 31 and 1% of the charge was removed as light hydrocarbon overhead through line 29. 83% of the charge was removed as a side stream through line 30. The material removed as a side stream was nitration grade toluene with a cloud point of 0°-10° F.

While the above example has been given showing the application of the present invention to the production of substantially dry toluene, it will be evident that it is generally applicable to the drying of hydrocarbons having boiling points above propane.

Having fully described and illustrated the practice of the present invention, what we desire to claim is:

1. A method for drying a hydrocarbon fraction containing dissolved water comprising the steps of passing a hydrocarbon fraction at a temperature of the order of 345° F. and boiling above 200° F. and containing approximately 1% of water dissolved therein into a flashing zone maintained at a pressure of the order of 2 atmospheres, removing approximately one-half of the dissolved water in conjunction with hydrocarbons in vaporous form from said flashing zone, condensing said vapors and separating the condensed vapors into a water fraction and a hydrocarbon fraction, removing the unvaporized ma-

5 terial from said flashing zone, admixing the hydrocarbon fraction therewith and distilling the admixture to separate substantially the remainder of said water as overhead and a substantially dry hydrocarbon fraction as a side stream.

2. A method for dehydrating a hydrocarbon fraction containing dissolved water comprising the steps of heating a fraction consisting essentially of 83% toluene, 16% of other hydrocarbons and 1% of dissolved water to a temperature of approximately 345° F. at a pressure of approximately 10 atmospheres, reducing the pressure of the heated fraction to approximately 2 atmospheres and removing hydrocarbon vapors therefrom and approximately one-half of the water originally dissolved in said charging stock, condensing said mixture and separating the condensed vapors into a water component and a hydrocarbon component, admixing the hydrocarbon component with the unvaporized portion of the fraction and discharging the admixture into a distillation zone maintained at a pressure in the range of 1 to 2 atmospheres, removing an overhead from said distillation step including substantially the remainder of the water originally dissolved in the hydrocarbon fraction and a substantially dry hydrocarbon as a side stream.

3. A method in accordance with claim 2 in which the hydrocarbon material other than toluene in the charging stock includes constituents lower boiling and higher boiling than the toluene and in which the lower boiling hydrocarbon is removed from the distillation step as overhead and the higher boiling hydrocarbon is removed as bottoms.
